BACK SUPPORT CUSHION

Billy E. Kirby, 938 Vinecrest Lane,
Richardson, Tex. 75080

Filed Oct. 29, 1974, Ser. No. 518,550

Term of patent 14 years

Int. Cl. D6—09

U.S. Cl. D6—201

FIG. 2

FIG. 1 is a front perspective view of a back support cushion showing my new design; and

FIG. 2 is a rear and bottom perspective view.

I claim:

The ornamental design for a back support cushion, substantially as shown.
